UNITED STATES PATENT OFFICE.

JOHN J. BOAX, OF MCKEESPORT, PENNSYLVANIA, ASSIGNOR TO NATIONAL TUBE COMPANY, OF PITTSBURG, PENNSYLVANIA, A CORPORATION OF NEW JERSEY.

FURNACE-CHARGING DEVICE.

SPECIFICATION forming part of Letters Patent No. 794,391, dated July 11, 1905.

Application filed March 8, 1904. Serial No. 196,337.

To all whom it may concern:

Be it known that I, JOHN J. BOAX, a resident of McKeesport, in the county of Allegheny, and State of Pennsylvania, have invented a new and useful Improvement in Skelp-Turning Devices; and I do hereby declare the following to be a full, clear, and exact description thereof.

My invention relates to machines for charging tubular skelps into furnaces; and the object is to improve machines of this kind by providing means whereby the skelp can be easily rotated before charging, so that the lap-joint will be in proper position when the skelp is in the welding-furnace.

In the manufacture of lap-weld pipe the flat plates are provided with beveled or scarfed edges and are then bent into approximately tubular form known as "skelp." These skelp are then charged into the welding-furnace and as they heat are gradually rolled sidewise until in line with the withdrawing-opening and when at the proper heat are withdrawn from the furnace and passed through welding-rolls and over a mandrel. In order to secure the greatest pressure on the lapped edges of the pipe, it is necessary that said joint be on the upper side of the skelp when it enters the rolls, and as a consequence it is essential that the lap-joint be on the upper side when the skelp rests in its withdrawing position during the final heating stages. This is also of importance, for the reason that there will be less tendency of the skelp as it softens under the heat to collapse under its own weight, as might occur with very heavy skelp in case they were in such position that the lap-joint were either at the bottom or at one side. Inasmuch as it is difficult to rotate large-sized skelp in the furnace, care is always exercised to charge them into the furnace with the lap in such position that when the skelp has been rolled over to its final heating position said lap will come on the upper side of the skelp. It is the practice, therefore, to position the skelp in the charging-trough before charging the same into the furnace. The weight of skelp for very large-sized pipes, however, is such that

their rotation in the trough of the charging-machine is a difficult matter.

The object of my invention is to provide means on the charging-machine whereby the rotation of heavy skelp for large-sized pipes becomes a comparatively easy matter.

To this end it consists, generally speaking, in providing the charging-machine with means for raising the skelp out of the charging-trough, said means comprising antifriction-supports for the skelp, whereon it can be readily rotated by hand or otherwise, and said means being also arranged to again lower the skelp into the trough.

In the accompanying drawings, Figure 1 is a side view of a charging-machine with my improvement applied thereto. Fig. 2 is a plan view of the same. Fig. 3 is a side view of a portion thereof on an enlarged scale. Fig. 4 is a plan view of a portion thereof on an enlarged scale. Fig. 5 is a cross-section on the line 5 5, Fig. 2. Fig. 6 is a similar section on the line 6 6, Fig. 2; and Fig. 7 is a view similar to Fig. 6, showing the skelp-lifting means in a different position.

My invention will be employed with a lap-weld furnace of any suitable description, the end of the furnace being shown at 1 and provided with a charging-opening 2 and other openings 3 arranged for the insertion of a picker-bar, whereby the skelp can be rolled sidewise in the furnace or for the insertion of a pusher-out bar, all as is now the practice with furnaces of this character.

In front of the furnace are a series of tracks 5, on which move wheels 6 of the laterally-moving charging-machine, this machine being adapted to be moved laterally thereon by any suitable mechanism, such as a motor 7, geared to a longitudinal shaft 8, connected to the wheels of the carriage. This charging-machine is provided with a longitudinal frame 9 composed of channel-beams 10, forming ways for the movement of the pushing-carriage 11, which is provided with a standard 12, carrying the pivoted pushing-fork 13. This carriage may be traversed back and forth by any suitable mechanism now used for that pur-

pose, in the drawings there being shown for this purpose an endless cable 15, passing around a suitable guide-sheave 16 at the front end of the machine and connected to a drum 18 on the rear end of the machine and driven by any suitable motor, such as the electric motor 19. At the forward end of the machine is provided a trough 20 for receiving the skelp 21, in which it rests while being pushed into the furnace. At one side will be provided a suitable support, such as the skids 22, upon which the skelp are received and from which they are delivered to the trough 20, it being the practice to move the machine laterally close to the support 22, roll a skelp into the trough 20, then move the machine back into line with the charging-opening of the furnace, and then push the skelp out of the trough into the furnace.

20 The machine so far described is practically old, and all of the features so far described may be of any of the usual or permissible forms for accomplishing these purposes, the specific structure shown having been selected largely for purposes of illustration.

It will be obvious that with large heavy skelp resting in the V-shaped trough 20 some difficulty might be met with in rotating the same, so as to get the lap in the proper position. The side walls of the V-shaped trough offer considerable friction against the rotation of the skelp, and this part of the work has been found to be quite difficult. My invention provides means whereby the skelp will be raised up out of contact with the walls of the trough 20 and rests upon antifriction members, so that the rotation thereof will become easy. A large variety of means for thus raising the skelp out of contact with the trough 30 may be provided. As shown in the drawings, the longitudinal beams 10 of the charging-machine are provided at two points with vertical ways 25, in which are mounted vertically-reciprocating members 26, having their upper ends bent inwardly and provided with suitable antifriction devices, such as rollers 27, mounted on journals parallel to the axis of the skelp. The lower ends of the members 26 are connected to a cross-piece 29, so that the vertical and bottom members, in effect, form a yoke inclosing the longitudinal beams 10 of the machine-frame. The trough 20 will be cut away wherever these lifting-yokes are provided, and in practice the trough preferably 45 will be formed in sections, as indicated in the drawings. In the drawings only two lifting-yokes are shown; but it is obvious that any number greater than two may be employed, and they will be symmetrically arranged with reference to the ends of the skelp, so that substantially equal portions of the weight of the skelp will be carried by the several lifting-yokes. These lifting-yokes will be raised and lowered 50 by any suitable means, so as to lift the skelp

out of contact with the side walls of the trough. 65 I have shown for this purpose stationary wedge-shaped blocks 30, secured on the floor of the mill in such position as to contact with the cross-bars 29 of the yokes. Preferably rollers or wheels will be mounted in said 70 cross-bars to reduce the friction on the blocks 30. These blocks preferably will be located adjacent to the skids 22, so that when the charging-machine is moved over into proximity to the skids to receive a skelp the rollers 75 31 will run onto the inclined blocks 30, thus raising the yokes to the position shown in Fig. 6. As a consequence when a skelp is rolled onto the machine it will rest upon the rollers 27 and not in the trough 20. In this 80 position no matter what the weight of the skelp may be it can be easily rotated, so as to bring the lap to the proper position. When the carriage is moved back into line with the charging-opening of the furnace, the rollers 85 31 will run down the inclined blocks 30, thus permitting the lifting-yokes to drop and lower the skelp into the charging-trough 20. The arrangement is such that the rollers 27 will drop entirely below the supporting-faces of 90 the trough 20, so that the tube will be held by the trough while being charged, thus subjecting the same to sufficient friction to prevent the same from rotating while being charged and making it practically impossible 95 for the lap to get out of proper position.

The operation of the lifting mechanism will be readily understood from the foregoing description. It is of such a nature that no operation not now necessary with the charging-machines need be employed, the mere act of running the carriage over to the skids to receive a skelp and again running it back into line with the charging-opening of the furnace sufficing to raise and lower the lifting means. 100 The antifriction-rollers in the upper ends of the lifting-yokes form a support for the skelp, upon which the latter can be very easily rotated. This makes it possible with only a slight effort to bring the lap of the skelp into 105 proper position for charging into the furnace, so that after said skelp has been rolled over to the withdrawing position in the furnace said lap will be on the upper side of the skelp.

Various modifications may be made in the 110 details of the construction of the devices described without departing from the spirit thereof.

What I claim is—

1. In a skelp-charging machine, the combination with a furnace, of a charging-trough in front of the same, a pusher arranged to reciprocate longitudinally of said trough to push the skelp out of the same and into the furnace, and antifriction devices arranged to support the skelp and permit its rotation and to then deposit the same in said trough. 120

2. In a skelp-charging machine, the combi-

nation with a furnace, of a skelp-support in front of the same, a pusher arranged to reciprocate longitudinally of said support, and vertically-movable antifriction members arranged to support the skelp out of contact with the support to permit its rotation and then lower the same onto said support.

3. In a skelp-charging machine, the combination with a furnace, of a V-shaped charging-trough in front of the same, a pusher arranged to reciprocate longitudinally of said trough to push the skelp out of the same and into the furnace, a vertically-movable member mounted on said trough and having its upper end 15 extending crosswise of said trough and arranged when elevated to support the skelp out of contact with the trough to permit its rotation, and means for raising and lowering said member.

2c 4. In a skelp-charging machine, the combination with a furnace, of a charging-trough in front of the same, a pusher arranged to reciprocate longitudinally of said trough to push the skelp out of the same and into the furnace, vertically-movable members mounted on said trough, means for raising and lowering the same, and antifriction devices carried by said members and arranged to support the skelp out of contact with said trough to permit its rotation.

35 5. In a skelp-charging machine, the combination with a furnace, of a charging-trough in front of the same, a pusher arranged to reciprocate longitudinally of said trough to push the skelp out of the same and into the furnace, vertically-movable yokes mounted on said trough, means for raising and lowering said yokes, and antifriction means on said yokes and arranged to support the skelp out 40 of contact with the trough.

45 6. In a skelp-charging machine, the combination with a furnace, of a charging-trough in front of the same, a pusher arranged to reciprocate longitudinally of said trough to push the skelp out of the same and into the furnace, vertically-movable yokes mounted on said trough, a pair of rollers carried by said yokes on axes parallel to the trough, and means for raising and lowering said yokes.

50 7. In a skelp-charging machine, the combination with a furnace, of a carriage movable laterally in front of the same, a skelp-support on said carriage, a pusher arranged to reciprocate longitudinally of said support to push the skelp into the furnace, vertically-movable members mounted on said carriage, antifriction members arranged on the upper ends of said vertically-movable members to lift the skelp off the skelp-support, and means at one 55 side of said furnace for lifting said vertically-movable members.

60 8. In a skelp-charging machine, the combination with a furnace, of a carriage arranged to move laterally in front of the same, a skelp-

support on said carriage, a pusher arranged 65 to reciprocate longitudinally of said support, vertically-sliding members mounted on said carriage and arranged to lift the skelp off said support, and stationary inclined ways so located that said sliding members will contact 70 therewith in the lateral movement of the carriage and be lifted thereby.

9. In a skelp-charging machine, the combination with a furnace, of a carriage mounted to move laterally in front of the same, a skelp- 75 support on said carriage, a pusher arranged to move longitudinally of said support, vertically-movable members mounted on said carriage, antifriction devices carried by said members and arranged to engage the skelp, 80 and inclined stationary members with which said vertically-movable members contact in the lateral travel of the carriage and whereby said members are lifted to raise the skelp off the skelp-support. 85

10. In a skelp-charging machine, the combination with a furnace, of a carriage laterally movable in front of the same, a skelp-support on said carriage, a pusher arranged to reciprocate longitudinally of said support, 90 vertically-movable yokes mounted on said carriage, a pair of rollers carried by each yoke on axes parallel to the skelp-support, and inclined stationary ways with which the lower ends of said yokes contact in the lateral travel 95 of the carriage and whereby they are raised.

11. In a skelp-charging machine, the combination with a furnace, of a carriage laterally movable in front of the same, a skelp-support on said carriage, a pusher arranged 100 to move longitudinally of said skelp-support, vertically-movable members mounted on said carriage, a pair of rollers mounted in the upper ends of each of said vertically-movable members, a roller in the lower end of each of the vertically-movable members, and stationary wedge-blocks arranged in the path of the rollers in the lower end of said vertically-movable members in the lateral movement of the carriage and serving to raise said members. 110

12. In a skelp-charging machine, the combination with a furnace, of a carriage laterally movable in front of the same, a charging-trough on said carriage, a pusher arranged to 115 reciprocate longitudinally of said trough, vertically-movable members mounted in said carriage and projecting into said trough, antifriction devices carried by said members, rollers in the lower ends of said members, and stationary inclined ways arranged in the path of movement of said rollers and adapted in the lateral movement of the carriage to elevate said members. 120

13. In a skelp-charging machine, the combination of a carriage, a trough on said carriage, a pusher arranged to reciprocate longitudinally of said trough, vertically-movable

members mounted on said carriage and arranged to lift the skelp out of the trough, and antifriction devices carried by the upper ends of said members and arranged to support the skelp.

14. In a skelp-charging machine, the combination of a carriage, a trough on said carriage, a pusher arranged to reciprocate longitudinally of said trough, vertically-movable

yokes mounted on said carriage and arranged to lift the skelp out of the trough, and anti-friction-rollers carried by said yokes.

In testimony whereof I, the said JOHN J. BOAX, have hereunto set my hand.

JOHN J. BOAX.
